US0D1074585S

(12) **United States Design Patent** (10) **Patent No.:** **US D1,074,585 S**
(45) **Date of Patent:** **** May 13, 2025**

(54) **DUAL WIRELESS CHARGER CASE**

(71) Applicant: **Nomad Goods, Inc.**, Santa Barbara, CA (US)

(72) Inventors: **Brian Hahn**, Santa Barbara, CA (US); **Tanner Walker**, Santa Barbara, CA (US); **Nick Walden**, Santa Barbara, CA (US); **Olivia Xu**, Santa Barbara, CA (US); **Ryan Thomas**, Santa Barbara, CA (US); **Mulin Yang**, Goleta, CA (US); **Tane Martin**, Santa Barbara, CA (US)

(73) Assignee: **Nomad Goods, Inc.**, Santa Barbara, CA (US)

(**) Term: **15 Years**

(21) Appl. No.: **29/825,919**

(22) Filed: **Feb. 7, 2022**

(51) LOC (15) Cl. **13-02**
(52) U.S. Cl. **USPC D13/108**

(58) **Field of Classification Search**

(57) **CLAIM**

The ornamental design for a dual wireless charger case, as shown and described.

DESCRIPTION

FIG. 1 is a top perspective view of a dual wireless charger case;
FIG. 2 is a bottom perspective view thereof;

FIG. 3 is a top view thereof;

FIG. 4 is a bottom view thereof;

FIG. 5 is a front view thereof;

FIG. 6 is a right-side view thereof;

FIG. 7 is a back view thereof; and,

FIG. 8 is a left-side view thereof.

The broken lines shown represent unclaimed subject matter and form no part of the claimed design.

1 Claim, 4 Drawing Sheets
